CLAIM

The ornamental design for an LCD monitor with TV streaming stick socket, as shown and described.

DESCRIPTION

FIG. 1 is a perspective view of an LCD monitor with TV streaming stick socket showing my new design;

FIG. 2 is an alternative perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front view of the LCD monitor with TV streaming stick socket of FIG. 1, shown in an alternative configuration;

FIG. 10 is an enlarged view of the portion labeled as "10" in FIG. 1;

FIG. 11 is an enlarged view of the portion labeled as "11" in FIG. 2;

FIG. 12 is an enlarged view of the portion labeled as "12" in FIG. 3;

FIG. 13 is an enlarged view of the portion labeled as "13" in FIG. 5;

FIG. 14 is an enlarged view of the portion labeled as "14" in FIG. 6;

FIG. 15 is an enlarged view of the portion labeled as "15" in FIG. 6;

FIG. 16 is an enlarged view of the portion labeled as "16" in FIG. 7; and,

FIG. 17 is an enlarged view of the portion labeled as "17" in FIG. 8.

Dot-Dash broken lines seen in the drawings represent the boundaries of the enlarged portions and form no part of the claimed design. All other broken lines depict portions of the LCD monitor with streaming stick socket that form no part of the claimed design.
